KARL MÜLLER, OF NEW YORK, N. Y., ASSIGNOR TO NICHOLAS MÜLLER, OF SAME PLACE.

Design No. 3,646, dated August 31, 1869.

DESIGN FOR A PAIR OF FIGURES.

The Schedule referred to in these Letters Patent and making part of the same.

To all whom it may concern:

Be it known that I, KARL MÜLLER, of the city, county, and State of New York, have invented a new and useful Design for a Pair of Figures; and I do hereby declare that the following is a full and exact description thereof, reference being had to the accompanying drawing, forming a part of this specification, representing the design in perspective.

This invention relates to a design for a pair of figures, representing two boys playing the "national" game of base-ball in miniature, and consists of two parts—one part representing the batter, or striker, Figure 1, and the other part the pitcher, Figure 2.

The batter stands with his legs astride, both his hands in front of him, holding a stick, or bat, which rests upon the ground. His face, smiling, is turned sideward, on the lookout for a ball.

The pitcher stands, also, with his legs apart. In his left hand, at his side, he holds his base-ball cap. In his right, which he holds extended from him, he has a ball, ready to pitch to the batter. A handkerchief is tied around his neck, which is streaming in the wind. His mouth is wide open, bellowing to his mate to "Look out."

The base on which the figures stand (which is the same for both) is octagonal in form, with this inscription of Thackeray's around it, "Fun is good, truth is better, but love is best of all."

The figures are fastened to the top part a a of the base, which may be detached from the portion b b, which is hollow, and serves for a match-safe.

What I claim as my invention, and desire to secure by Letters Patent, is—

The design for a pair of figures, as herein shown and described.

KARL MÜLLER.
